United States Patent Office.

E. J. LEYBURN, OF LEXINGTON, VIRGINIA.

Letters Patent No. 94,618, dated September 7, 1869.

IMPROVED APPARATUS FOR PROPELLING MACHINERY.

The Schedule referred to in these Letters Patent and making part of the same.

To all whom it may concern:

Be it known that I, E. J. LEYBURN, of Lexington, in the county of Rockbridge, and State of Virginia, have invented a new and improved Mechanical Movement for Operating Sewing-Machines and other Light Machinery; and I do hereby declare that the following is a full, clear, and exact description thereof, reference being had to the accompanying drawings, making part of this specification, in which—

Figure 1 is a longitudinal section, taken vertically through the centre of the mechanical movement adapted for operating a sewing-machine.

Figure 2 shows the rocking-frame, inclined forward.

Figure 3 is a rear end view of the seat and rocking-frame.

Similar letters of reference indicate corresponding parts in the several figures.

This invention relates to a new and improved mode of operating light machinery, such as sewing-machines and watch-makers' lathes, and is intended to remedy the objections attending the treadle-movement, and, in lieu of such movement, employ the weight of a person sitting at a machine to assist such person in obtaining the required power to drive it.

The main object of my invention is to arrange the frame of the machine to be operated, and the seat of the operator thereof, upon a pivoted frame, in such manner that by a light swaying motion of the operator a rocking motion can be imparted to said frame, from which the necessary power and motion can be derived to operate the machine, as will be hereinafter explained.

To enable others skilled in the art to understand my invention, I will describe its construction and operation.

In the accompanying drawings—

A represents a rectangular base-frame, having two ears, *f f*, rising from its longitudinal side-bars, to which another rectangular frame, B, is pivoted by means of a horizontal cross-rod, *e*.

The frame B is allowed to receive a vertical rocking motion about its fulcrum or pivot-rod *e*, and between the two frames A B, at their ends, springs are applied, to give uniformity to the rocking movements of frame B.

The spring *d* may be of the semi-elliptical kind, and the springs *S* may be of a similar kind, or they may be made of India rubber.

Upon the frame B, on one side of the fulcrum *e*, is constructed a frame E, on which rests a seat, F, for the operator, which seat can be adjusted to suit different persons by loosening the clamp-screw *h*, that passes through the boards G G.

On the opposite side of the fulcrum *e*, a frame, D,

is erected upon frame B, on top of which is a table, J, carrying a sewing-machine, K, or some other light driving-machine.

L is a balance-wheel, carrying a belt, *g*, which communicates rotary motion to the driving-shaft of the sewing-machine K, and T is a pitman, which is connected at one end to a wrist-pin, eccentrically placed on one side of the wheel L, and at the other end to the longest arm of a vertically-vibrating lever, N.

This lever N is pivoted, at *p*, to the frame E, and its shortest arm is connected by a link, *r*, to the rear end of the base-frame A, at *s*.

It will be seen that rotary motion will be communicated to the balance-wheel L by vibrating the frame B, and that a very slight motion of this frame is required to effect the object.

On the front end of the frame B, at the middle of the length of the front cross-bar, an adjustable foot-rest, *c'*, is applied, which can be adjusted vertically by loosening set-screw *b'*, and opposite the foot-rest *c'*, adjustable toe-rest *c*, a toe-board is applied to the front cross-bar *a* of the frame A, and held at any desired height by the set-screw *b*, on which board a spring cushion might be applied.

The operator sits upon the chair F, with the feet upon the floor, or preferably upon the stand *c'*, and with the hands upon the table J, in a natural position for guiding the work.

The balance-wheel may then be started by hand, after which a slight forward and backward motion of the body will rock the frame B, and keep it in motion.

I have applied a toe-rest, *c*, in such relation to the foot-rest *c'* that the operator can at will use his toes to assist in rocking the frame B.

The principle of my invention consists in mounting the operator, and also the machine which it is intended to operate, upon a frame, in such manner that by a slight forward and backward movement of his body, the operator can derive motion and power sufficient to drive the machine; and while I prefer to communicate motion to the machine to be driven from the frame B, by means of lever N, pitman T, and balance-wheel L, I do not confine myself to these parts, as other equivalent means may be adopted. Nor do I confine myself to the foot-stand, the toe-board, or the springs *d S*, but prefer to adopt these parts, and apply them substantially as set forth.

The fulcrum *e* may be made adjustable toward or from the rear of the frame A, so as to adapt the machine to be operated conveniently, either by a very heavy person or by a very light person.

Having described one practical mode of carrying my invention into effect,

What I claim as new, is—

1. A table for supporting the machine to be operated, and an operator's seat or support, both mounted upon a vibrating frame, B, or its equivalent, and provided with such means as will transmit motion from said frame to said machine, substantially as described.
2. The adjustable seat F, on rocking frame B, substantially as described.
3. Spring or springs applied between the frames A B, substantially as described.

4. The foot-stand c', applied to the frame B, substantially as described.
5. The toe-rest c, applied to frame A, substantially as described.

E. J. LEYBURN.
